ELECTRIC ORGAN

Joseph Palma, Jr., Wheaton, Ill., assignor to Hammond Organ Company, Chicago, Ill., a corporation of Delaware

Filed Sept. 25, 1959, Ser. No. 57,687

Term of patent 14 years

(Cl. D56—2)

Fig. 1

Fig. 2.

Fig. 1 is a perspective view of an electric organ, showing my new design;

Fig. 2 is an end elevational view of the organ taken from the right side of Fig. 1.

The top and back of the organ are plain, and the left side is a counterpart of the side shown in Fig. 2.

The dominant features of my design reside in the portion shown in full lines.

I claim:

The ornamental design for an electric organ as shown and described.
